US00D630809S

(12) **United States Design Patent**
Dye et al.

(10) **Patent No.:** **US D630,809 S**
(45) **Date of Patent:** **** Jan. 11, 2011**

(54) **POOL CLEANER**

(75) Inventors: **G. Frank Dye**, Winston Salem, NC (US); **Marchal Depasquale**, Morris Plains, NJ (US); **Paul V. Watkins**, Pfafftown, NC (US); **Benoit Orban**, St-Lambert (CA); **Mario Gagnon**, Ste-Adele (CA)

(73) Assignee: **Hayward Industries, Inc.**, Elizabeth, NJ (US)

(**) Term: **14 Years**

(21) Appl. No.: **29/339,532**

(22) Filed: **Jul. 1, 2009**

(51) **LOC (9) Cl.** **15-05**

(52) **U.S. Cl.** **D32/21**

(58) **Field of Classification Search** **D32/1, D32/21; 15/1.7; 29/596; 137/114, 907, 137/899; 210/167.1, 167.12, 167.15, 167.16, 210/167.18; 134/21; 180/306; 901/1; D15/7**
See application file for complete search history.

Primary Examiner—Ruth McInroy*(74) Attorney, Agent, or Firm*—McCarter & English, LLP(57) **CLAIM**

The ornamental design for a pool cleaner, as shown and described.

DESCRIPTION

FIG. 1 is a perspective view of a pool cleaner showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The details shown in broken lines form no part of the claimed design.
